UNITED STATES PATENT OFFICE.

THOMAS R. MICHEL, OF SANDUSKY, OHIO, ASSIGNOR OF ONE-THIRD TO BERT F. KEECH
AND ONE-THIRD TO FRED J. HINKEY.

COMBINED FERMENTING BUNG AND WIRE JAR HOLDER.

Application filed May 23, 1923. Serial No. 640,942.

To all whom it may concern:

Be it known that I, THOMAS R. MICHEL, a citizen of the United States, residing at Sandusky, in the county of Erie and State 5 of Ohio, have invented certain new and useful Improvements in Combined Fermenting Bungs and Wire Jar Holders; and I do hereby declare the following to be a full, clear, and exact description of the invention, 10 such as will enable others skilled in the art to which it appertains to make and use the same.

This invention relates to devices used in the fermenting of wine, and more particularly to a liquid seal vent device, such as is commonly used in connection with casks to permit the escape of the vapors produced during the fermenting process while at the same time preventing access of air to the 20 contents of the cask.

Various devices of this general character are well known, but the objects of the present invention is to provide a device of an improved and simplified structure, lending 25 itself to economical manufacture and adapted to use with a large variety of sizes of tumblers and bung stoppers.

The invention consists in the novel construction, arrangement and combination of 30 parts as hereinafter more particularly described and claimed.

One sheet of drawings accompanies this specification as part thereof, in which like reference characters indicate similar parts 35 throughout, and in which,—

Figure 1 is a side elevation of the improved device, partly broken away;

Fig. 2 is a vertical section of a portion of the stopper showing the application of the 40 bracket; and

Fig. 3 is a plan view showing the stopper in horizontal section.

In accordance with the present invention a bung stopper 1 having a central bore 3 45 and an extension nipple 2 is provided near its top with an annular groove 5. A short piece of rubber tubing 4 is adapted to be attached to the nipple 2 to convey vapors arising

from the fermenting juices contained in the cask (not shown), in the bung of which 50 the stopper 1 is adapted to be positioned.

A bracket 7 is formed from a piece of suitable heavy wire or rod 6 made from suitable resilient metal. The rod 6 is bent adjacent its ends into rings 8 and 9, these 55 rings being preferably left open as at 10 to permit their being sprung either in or out to varying sizes. The rings 8 and 9 are formed to lie in parallel but spaced planes as illustrated in Figure 1, so that when ring 60 8, for instance, is sprung into the annular groove 5 of stopper 1, ring 9 will be positioned by rod 6 at an elevation above stopper 1 and in proper position to receive a tumbler 11 containing a suitable fluid such 65 as alcohol into which the free end of the tube may be submerged.

It will be apparent that the rings 8 and 9, as above indicated, may be sprung to adapt same to varying sizes of stoppers and 70 tumblers, and that in conjunction with the annular groove 5 the construction described permits the rotation of the bracket to any position desired relative to the stopper.

Having thus fully described my invention, 75 what I claim is,—

1. A device of the character described comprising in combination a perforated stopper provided with an annular groove adjacent its top and a bracket comprising 80 a rod bent at its ends into two ring parts lying in parallel spaced planes, one of said rings adapted to seat in the annular groove of the stopper.

2. The combination of a perforated stopper having an annular groove adjacent its top, and a bracket of suitable stiff and resilient wire bent adjacent its ends into two partly open rings, said rings lying in parallel spaced planes, one of said rings adapted 85 to seat in said annular groove in the stopper and the other adapted to accommodate a tumbler or the like.

In testimony whereof I affix my signature.

THOMAS R. MICHEL.
